UNITED STATES PATENT OFFICE.

DAVID HENRY ELKINS, OF AMESBURY, MASSACHUSETTS, ASSIGNOR TO GRAY & DAVIS INC., OF CAMBRIDGE, MASSACHUSETTS.

DESIGN FOR A LAMP.

50,241.

Specification for Design.

Patented Jan. 30, 1917.

Application filed October 18, 1915. Serial No. 56,617. Term of patent 7 years.

To all whom it may concern:

Be it known that I, DAVID HENRY ELKINS, a citizen of the United States, and resident of Amesbury, in the county of Essex and State of Massachusetts, have invented a new, original, and ornamental Design for Lamps, of which the following is a specification.

Figure 1 is a view in side elevation of a lamp embodying the new design. Fig. 2 is a perspective view of the same.

I claim:

The ornamental design for a lamp, as shown.

Signed at Amesbury in the county of Essex and State of Massachusetts this fifth day of October A. D. 1915.

DAVID HENRY ELKINS.
